ATTORNEYS

UNITED STATES PATENT OFFICE.

GEORGE PARKER CRAGIN, OF SPOKANE, WASHINGTON.

SHIRT.

Application filed October 1, 1919. Serial No. 327,685.

To all whom it may concern:

Be it known that I, GEORGE PARKER CRAGIN, a citizen of the United States, residing at Spokane, in the county of Spokane and State of Washington, have invented new and useful Improvements in Shirts, of which the following is a specification.

My invention relates to improvements in soft shirts, and has particular reference to the sleeve and cuff constructions thereof.

An important object of the invention is to provide means whereby the shirt may be equipped with a detachable soft folded cuff, which may be reversed when desired.

A further object of the invention is to provide means for securing the soft folded cuff to the sleeve of the shirt, in a manner for producing the forward straight edge effect between the cuff and the sleeve, as is obtainable with the ordinary sewed on cuff.

A further object of the invention is to provide a tab permanently secured to the soft folded cuff, which tab may be employed when the cuff is folded or reversed in either direction, and is adapted for cooperation with an ordinary straight headed button in securing the cuff to the sleeve of the shirt, thereby dispensing with the necessity of employing any particular form of jewelry for securing the cuff in place.

A further object of the invention is to provide reinforcing means which is adapted for insertion within the folds of the cuff, to stiffen the same and impart thereto a neat and attractive appearance.

Other objects and advantages of the invention will be apparent during the course of the following description.

In the accompanying drawings forming a part of this specification and in which like numerals are employed to designate like parts throughout the same,

Figure 1 is a perspective view of a cuff and sleeve embodying my invention, showing the same in the assembled position;

Figure 2 is a side elevation of the same, showing the front straight edge effect;

Figure 3 is a perspective view of the sleeve, with the cuff removed, and parts disconnected;

Figure 4 is a perspective view of the cuff, the same being opened or unfolded to show the several buttonholes;

Figure 5 is an elevation of the inner side

of the cuff, unfolded, to illustrate the reinforcing means,

Figure 6 is a detail section taken through the end of the cuff, at the connecting tab,

Figure 7 is a similar view, showing a slightly modified form of connecting tab,

Figure 8 is an enlarged detail section taken on line 8—8 of Figure 2,

Figure 9 is an enlarged longitudinal section taken on line 9—9 of Figure 5,

Figure 10 is a perspective view of one of the reinforcing elements.

In the drawings, wherein for the purpose of illustration is shown a preferred embodiment of my invention, the numeral 15 designates the sleeve of a soft shirt, having the usual longitudinal opening 16 at the front edge thereof. This sleeve 15 which is illustrated is on the left side of the shirt, and the fly at the opening 16 embodies sides 17 and 18, as shown. The numeral 19 designates a wrist-band, which is stitched to the sleeve 15 at 20, the sleeve 15 projecting into the rear end of the wrist-band, the wrist-band being as usual made of two or more plies of fabric. The outer side 17 of the fly projects forwardly beyond the sleeve 15 and enters the rear end of the wrist-band 19, for a substantial distance, as shown at 21, while the inner side 18 is shortened and terminates at the inner edge of the wrist-band 19, affording a slit 22, and forming a foldable extension 23 upon one end of the wrist-band. This extension is adapted to be folded transversely upon a line 24, and is provided with a button-hole 25, as shown. The opposite end of the wrist-band is provided with a button-hole 26. The inner edge of the wrist-band 19 is preferably straight, while its outer edge is inclined from a point equidistantly spaced from the ends thereof toward such ends, whereby the sides of the wrist-band taper toward their free ends, as clearly indicated in Figure 2. The wrist-band is wider at its center than at its ends in order that it may be wide enough at the center to supply enough surface for the cuff to rest upon so that the cuff will not have a tendency to slip off the wrist-band to the annoyance of the wearer. Moreover, the wrist-band tapers towards its free ends in order that it may be narrow at its ends to be adjusted in proper position without being too wide so as to interfere with the cuff-link illustrated

in Figure 2. The side 18 of the fly may be equipped with a button-hole 27, to receive a button 28 arranged upon the inner surface of the side 17, and secured thereto.

5 My cuff is designated as a whole by numeral 29. It comprises (preferably) two plies 30 of fabric as shown in Fig. 6 but if desired may comprise more than two plies. By reference to Fig. 4 it will be seen that 10 the plies are stitched to each other as indicated by 31. The cuff is foldable upon a longitudinal line 32, providing inner and outer portions or folds 33 and 34. These portions or folds are provided at their ends 15 with button-holes 35 and 36, to receive cuff buttons 48', which may be of the link type, if desired.

The inner fold 33 of the cuff is provided inwardly of and near the button-hole 35 20 with an extra length transverse button-hole 37, the outer wall 38 of which button-hole is worked in the regular manner, when the cuff is made, while the inner wall 39 of said button-hole is split and the separate plies 25 worked separately, also at the time that the cuff is made. This split side is provided for the insertion of a connecting tab 40, between the plies of the cuff, such tab being secured in place by transverse and longitudinal 30 stitches 42 and 42^a. The free end of the tab has a longitudinal button-hole 43, and this free end may be easily passed through the extra long transverse button-hole 37 to be arranged upon either side of the inner portion 33 of the cuff. This construction has the advantages of concealing the attached 35 end of the tab. In order to more fully bring out the arrangement above described it is well to bear in mind that generally all cuffs 40 are made up of no less than three plies or thicknesses of material and the cuff may be made of four or more of such thicknesses. The button-hole in which the tab 40 is secured, is a transverse button-hole and runs 45 cross-wise of the cuff and in a direction opposite from the regular link-receiving button-hole or in other words the portion nearest the end of the cuff is worked in the ordinary manner. However, the upper half of 50 this transverse button-hole is divided, i. e., where four plies comprise the cuff, there are 55 equally divided two sections, with two plies to each section and each of these sections is worked separately with respect to the remainder of the button-hole. Manifestly an entrance to the inside of the cuff through this upper portion of the button-hole is gained, and it is through this entrance that I insert the tab 40 and stitch it in place as 60 designated by 42 of Figure 4. The tab is thus suspended in the upper half of one section and by drawing the tab through the button-hole, either side of the cuff may be exposed for wear and the tab will always 65 be arranged on the inside of the cuff where

it may be readily secured to the button on the wrist-band.

In Figure 7, I have shown a connecting tab 44, which is identical with the tab 40, except that the attaching end of the tab is 70 forked by splitting or separating the plies of fabric to produce single layers and plies 45. One ply 45 rests above and one ply 45 rests below the material 33 and said plies are secured to material 33 by stitching at point 75 46. The button-hole 47 of material 33 of Fig. 7 is similar to button-hole 37 of Fig. 4 and for the same purpose. The tab 44 is also provided with a button-hole (not shown Fig. 7) similar to button-hole 43 of tab 40. When 80 a cuff provided with tab 44 is employed the button-hole (not shown) acts the same as button-hole 43 when a cuff having a tab 40 is employed.

As more clearly shown in Figures 5 and 85 9, the inner fold 33 is provided near its outer edge with longitudinal pockets 50, formed by longitudinal stitches 51, the outer end of these pockets being closed and access being had to the inner ends of these pockets through 90 a transverse inner button-hole 52. This button-hole 52 has a wide open mouth and is formed through the inner ply only of the fold 33. These pockets are adapted for the insertion of stiffening or reinforcing strips 95 53, which are preferably formed of celluloid, see Figure 10, and which may be removed when it is desired to launder the cuffs. These stiffening strips are positioned at the 100 forward edge of the cuff, and impart to the same a neat appearance, as if it were laundered. Before the cuff is reversed, the transverse button-hole 52 occurs at the transverse fold of the cuff, upon the inner side of 105 the inner portion of the cuff, and this arrangement prevents the reinforcing strips 53 from being accidentally displaced from within the pocket. When the cuff is reversed by folding the portions thereof upon the longitudinal fold so that the inner portion becomes the outer portion, the transverse button-hole is still at the transverse fold and arranged next to the wrist-band and this arrangement will prevent the accidental displacement of the reinforcing strips. 110 115 120

In the use of the cuffs and sleeve, the extension 23 of the wrist-band 19 is first folded inwardly upon the line 24, with a stud or collar-button 24' therein, the head of this stud projecting outwardly, as shown in Figure 1. The stud is then passed through the button-hole 26 and the wrist-band is thereby connected at its ends. The cuff 29, having the cuff buttons or links 48' passed through the button-holes 35 and 36, is then brought to a position to receive the wrist-band 19, the cuff buttons 48' being arranged outwardly of the tapered end of the wrist-band, as clearly shown in Figure 2. The connecting tab 40 is extended through the 125 130

button-hole 37 to be arranged upon the inner side of the inner portion 33, and this tab is now folded over the connected ends of the wrist-band and the stud 24' passed through 5 the button-hole 43. This having been done, the stud is next passed through the button-hole 48. The connection between the cuff and sleeve is such that the fly edge 49' of the sleeve and cuff have the straight edge effect. 10 As clearly appears from the drawings, it will be seen that the wrist-band comprises an added portion 23. This portion may be termed nothing more than the wrist-band of the ordinary construction. However, the 15 band is not stitched completely to its end with respect to the sleeve portion, and thus it is manifest that when the wrist-band is buttoned the portion 23 of the band that is not secured to the sleeve portion is really a 20 free end, and therefore can be bent under the upper portion of the band to produce an encircling member or band for the wrist. It should be remembered that the flaps 17 and 18 are buttoned so as to lay flat against 25 each other, whereas the portion 23 of the band is turned back on the line 24 so as to rest under the portion in which the button-hole 26 is worked in the band 19. This arrangement forms an encircling band somewhat after the manner of the neck-band of 30 a shirt.

When it is desired to reverse the cuff, such as the left cuff, the same is disconnected from the sleeve and the inner fold 33 turned upon 35 the longitudinal line so that it becomes the outer fold. The tab is drawn through the button-hole 37 to assume a position upon the opposite side of the portion of the cuff carrying it. The reverse cuff will now be 40 adapted to be applied to the right sleeve of the shirt. In a similar manner the right cuff may be removed and reversed and applied to the left sleeve.

It is to be understood that the forms of 45 my invention herewith shown and described are to be taken as preferred examples of the same, and that various changes in the shape, size and arrangement may be resorted to without departing from the spirit of my invention, or the scope of the subjoined claims.

Having thus described my invention, I claim:—

1. As an article of apparel, the combination of a shirt sleeve having a longitudinal 55 fly therein abutting sides formed by the fly, one of said sides being slightly increased in length with respect to its opposing side, a wrist band increased in width remote from its free ends; said band being secured to the lower end of the sleeve and constructed and arranged to terminate at a point in rear of one side of the sleeve and further being separated from the other side of the sleeve to permit folding of the increased portion 60 of the band on a transverse line, and a de-

tachable and double reversible fold soft cuff having a tab secured thereto for connection of said cuff with respect to the band.

2. An article of apparel, comprising a sleeve portion, a longitudinal opening 70 formed in the sleeve, abutting sides formed by the opening, a wrist-band secured on the end of the sleeve and having one of its ends terminating at a point slightly in rear of one abutting side of the sleeve and the opposite end of the band having a slight portion separated from the other abutting side of the sleeve; said last named portion being adapted to be folded upon itself, button-holes worked in each end of the band, and 80 a detachable and double reversible fold soft cuff having link receiving button-holes in the ends thereof, a transversely arranged button hole formed at one end of inner fold of the reversible cuff, a tab secured adjacent 85 the transversely arranged button hole and adapted to be drawn through the said button hole, a button hole arranged in the tab, a longitudinal button hole, arranged in an inner fold of the cuff at the end remote from 90 the tab.

3. As a new article of apparel, a sleeve having a longitudinal opening formed in its lower end, a wrist band tapered towards 95 its ends and secured to the sleeve; said sleeve having one of the sides that is formed by the opening extending slightly beyond one end of the wrist band, and the other side of the opening separated to a slight degree from the opposite end of the wrist band to enable the said end to be turned backwardly upon itself and button holes formed in each end of the wrist band whereby a stud may be passed through the button holes of the ends 100 to form a wrist encircling band with the sides 105 of the opening of the sleeve resting against each other.

4. As an article of apparel, a detachable foldable soft cuff provided near one end of the inner fold with a transverse button-hole, 110 a tab suspended therein and secured thereto, adapted to be drawn through said button-hole to assume positions upon opposite sides of the cuff, said tab having a button-hole.

5. A two or more ply detachable foldable soft cuff provided near one end of the inner fold with a transverse button hole, a tab arranged within said button hole and having one end thereof extending between the plies 120 of the cuff and attached thereto, said tab having a button hole formed in its free end.

6. As an article of apparel, a detachable double reversible fold soft cuff embodying inner and outer folds, the inner fold having longitudinal pockets provided with openings at approximately the middle of the length of the fold, and reinforcing strips adapted 125 for insertion within the longitudinal pockets.
